CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

TOOL FOR MANIPULATING SOCKET CAPS.

Application filed January 22, 1923. Serial No. 614,190.

To all whom it may concern:

Be it known that I, CARL E. ANDERSON, a citizen of the United States of America, residing at Stratford, in the county of Fairfield and State of Connecticut, have invented certain new and useful Improvements in Tools for Manipulating Socket Caps, of which the following is a specification.

My invention relates to a tool for manipulating socket caps, and particularly the cap of a socket casing of the multiposition catch type. The object of my invention is to provide a tool by which the cap may be conveniently manipulated within the husk 5 of an electric lighting fixture, without injury to the cap or its latching elements.

In the accompanying drawings—

Fig. 1 is a broken side elevation of a lighting fixture showing a socket cap installed; 20 Fig. 2 is a similar view showing the present tool applied to the cap;

Fig. 3 is a section on the line 3—3, Fig. 2;

Fig. 4 is a broken section on the line 4—4, 25 Fig. 3;

Fig. 5 is a section through the tool head alone, corresponding to Fig. 3, but showing the parts in a different position.

Electric lighting fixtures frequently comprise ornamental husks which surround the lamp socket and encase the latter so completely as to render the installation of the socket directly by hand extremely difficult, if not practically impossible. The present 35 invention provides a tool which facilitates the installation or the removal of the socket, and particularly of the cap element of the lamp casing which is commonly secured to the end of the fixture pipe. Inasmuch as 40 the cap has latching elements, deformation of which prevents their proper functioning, the tool is particularly designed to prevent injury thereto, while manipulating the cap.

As shown, the socket husk 10 is of tulip 45 shape, and its base 11 is secured to the threaded end 12 of the fixture pipe 13 either by threading directly thereon, or by means of a nut 14. The husk encases the lamp socket, of which cap 15 is shown in full lines in Fig. 1, and the cooperating shell 16 in broken lines. The cap 15 has the usual screw nipple 17 adapted to engage the threaded end 12 of the pipe 13. As will be observed, the husk 10 is of such length, and

of such narrow internal diameter that the 55 manipulation of the cap by hand within the husk, is at best a very difficult, if not an impossible, operation. After the cap 15 has been installed, the shell 16 is readily shoved up within the cap flange 18 and the cooperating latching elements automatically engage. The latching elements of the cap, as illustrated, are those indicated in my co-pending application Ser. No. 613,160, filed 60 January 17, 1923, and comprise an inwardly extending annular flange 19 at the lower margin of the cap to prevent endwise separation of the shell 16, together with one or more inwardly pressed ribs 20 adapted to take into apertures 21 in the telescoping area 65 of the shell and prevent relative rotation of the parts. The latching means, however, may be of any suitable type, and the present tool is not limited in its utility to a socket 70 having cap and shell fastenings of this particular type.

The tool comprises a tubular shank 22 carrying at one end a head 23 of a diameter slightly less than the internal diameter of the flange area 18 of the cap, so that it 80 will fit therein but be halted by the shoulder 24 of the cap, and thus accurately positioned within the flange area of the latter in operative position. Notches or recesses 25 are formed in the margin or periphery of 85 the tool head 23 to freely accommodate the inwardly struck ribs 20 of the cap flange. The tool head 23 is swivelled upon the hub 220 of the stem 22, and is held in position 90 thereon between a shoulder 26 on the stem, and a washer 27 above the head, the end 28 of the stem being spun over the washer 27 to permanently secure the head on the stem.

In order to establish an operative engagement, on the one hand between the tool head 23 and the flange 18 of the socket cap, and on the other hand between the stem 22 and the tool head 23, the head is slotted at 29 at substantially right angles to the axis of the stem, the slot cutting the central hole 30 in the head through which the stem passes. A cap-gripping member in the form of a plate 31 is arranged in the slot and is eccentrically pivoted at 32 on the rivet 33 passing through the tool head. At its inner edge the plate 31 is notched at 34 to provide a bearing face adapted to coop- 95 100 105

erate with a camming flat 35 cut in the side of the hub 220 of the stem 22 and facing the edge of the plate 31. The relation of the notch 34 and flat 35 is such that when their faces are parallel the plate 31 may be swung inward on its pivot 33 until its arcuate margin 36 coincides with, or lies within the peripheral boundary of the tool head. When, however, the stem 22 is rotated in either direction with respect to the head, one or the other end of the flat 35 bears against the face of the notch 34 and cams the plate outward into gripping engagement with the cap flange. The outward movement of the plate 31 is limited, however, by the engagement of its nose 37 against the face 38 of the slot 29, and the relation of these parts is such that while the outward throw of the plate 31 under the action of the cam flat 35 is sufficient to force the plate into gripping engagement with the flange of the socket cap, it is impossible to exert enough pressure on the latter to permanently deform it.

The limited throw of the plate also limits the swivelling action of the stem 22 with respect to the tool head 23, so that only a slight angular motion of the one with respect to the other is permitted, before a driving engagement is established. If desired, a spring may be provided between the grip plate and the head of the tool to maintain the plate normally in retracted position.

It will be noted that the plate is located in the arcuate area between the notches 25, which receive the ribs 20 of the cap, and that the plate 31 therefore engages the plain face of the cap flange unoccupied by the latching elements or ribs 20 which are thus in no danger of deformation by the plate 31. Any suitable means may be employed for rotating the tool stem 22, for instance, a pin passed through the hole 39 at the opposite end of the stem. It will also be noted that the stem 22 is hollow, so that the wire cable 40 which is led to the socket through the conduit 13, may be accommodated in the stem during the adjustment of the cap, although this is not necessary.

The operation of the tool will be readily understood. Assuming the husk 10 to have been secured to the pipe end, and the wire cable 40 drawn through the latter, the socket cap 15 is placed upon the tool head 23 in such position that its ribs 20 enter the notches 25, the stem 22 being in such relation to the head 23 that the plate 31 is retracted and lies within the peripheral area of the tool head. The cap thus positioned on the tool is then lifted into the husk, the wire cable 40 passing through the nipple of the cap, and into the hollow stem 22 of the tool. As the stem 22 is rotated to screw the cap nipple 17 on the threaded end 12 of the pipe, the resulting frictional drag causes the

stem to rotate with respect to the head 23 and thus to cam the plate 31 outward into gripping engagement with the cap flange. The effort exerted by the tool in screwing the cap firmly against the washer 14 is thus taken by the cap flange, and not by the latching elements 20. The latter are thus saved from possible distortion or injury due to shearing strains, which would otherwise be imposed thereon. After the cap is installed, it is only necessary to rotate the stem 22 slightly in the reverse direction to release the plate 31, whereupon the tool may be withdrawn from the cap. Should it be desired to remove the cap after installation, the tool is inserted in the cap and rotated in the reverse direction, with the result that the grip plate 31 is again thrown outward into gripping engagement with the cap flange, and the cap readily unscrewed.

Various modifications in detail of construction will occur to those dealing with the problem, without departing from the broader principle which I claim as my invention.

I claim—

1. In a tool of the character described, a head adapted to enter a socket cap and marginally recessed to engage latching elements in the cap, a member associated with said head and movable into gripping engagement with the cap in the area of the latter unoccupied by the latching elements, together with a tool stem rotatable with respect to said head and serving on displacement with respect to the latter to shift the cap-gripping member into engagement with the cap.

2. In a tool of the character described, a head adapted to enter a socket cap and marginally recessed to engage latching elements in the cap, a member associated with said head and movable into gripping engagement with the cap in the area of the latter unoccupied by the latching elements, together with a tool stem rotatable with respect to said head and serving on displacement with respect to the latter to shift the cap-gripping member into engagement with the cap, said tool stem being hollow for the accommodation of wires passing into the cap.

3. In a tool of the character described, a head adapted to enter a socket cap and marginally recessed to engage latching elements on the cap, said head being slotted in a plane normal to its axis, a gripping member pivoted in said slot, together with a tool stem rotatable with respect to said head, but having an operative engagement with said gripping member to displace the latter in the plane of the slot on rotation of the stem with respect to the tool head.

In testimony whereof I have signed my name to this specification.
